VAPORIZING BURNER

Ottley B. Lawrence, Gaffney, S. C.

Application September 7, 1929. Serial No. 390,880

3 Claims. (Cl. 158—91)

My invention relates to vaporizing oil burners of the stack plate type.

The invention has as its principal aim the improvement in the efficiency of such burners. Ex-

5 pressed in simple terms, my object is to get the most heat with the least oil, and I have attained this object to the extent of obtaining from 50 to 100 per cent more heat with the same oil. Ex-
10 pressed from another point of view, with a burn-
15 er of a given size I am able to get the same heat as heretofore obtainable with burners of this type with from 25 to 50 per cent less fuel.

The method of this operation consists in es-
15 tablishing a current of combustibles through the vaporizing channels coursing from the flame mouth of the burner backwardly through the lower channels, upwardly past the air inlet or ad-
20 vance ends of the channels and then inwardly through the upper channels to the body of the fire box or other chamber in which a burner is used, with a bypass of combustibles completing a circuit to the flame mouth of the lower channels; this current consisting of non-burning oil vapor in the lower channels and at the air inlet
25 or advance ends of the lower channel, burning vapor and admixed air at the advance ends of the upper channels, burned vapor and excess air in the inner ends of the upper channels, and burn-
30 ing vapor and admixed air in the flame mouth portions of the upper channels and emanating from the flame mouth ends together with excess liquid fuel, and finally excess liquid fuel, coursing downwardly and into the inner or flame mouth ends of the lower channels. This current

35 I establish by first heating the walls of the channels by burning a fuel below them with free ac-
cess of air to the channels from both ends, par-
ticularly from the air inlet or advance ends, and thereafter progressively cutting off direct access
40 of air to the advance ends of the lower channels from the bottom upwardly, whereby the flame from the burning fuel is progressively moved in the lower channels toward the inlet or advance ends and upwardly to the advance ends of the
45 upper channels where it burns with a portion of the entering air and pre-heats the remainder of the admitted air to oil vaporizing temperature, and whereby the flame passing through the upper channels, heats the walls of these channels to a
50 very high vaporizing temperature, a temperature sufficient to most effectually vaporize liquid fuel introduced toward the inner ends of these channels. The while I supply a liquid fuel slightly too fast to be completely vaporized in the upper
55 channels, whereby excess reaches the inner or

flame ends of the lower channels where it is va-
porized at the inception of the current of com-
bustibles, and continuity of the current is as-
sured.

The apparatus consists of a burner casing con-
60 taining a stack of spaced vaporizing elements,
preferably in the form of vaporizing plates sub-
stantially horizontally arranged and vertically
spaced, means to supply liquid fuel to the upper
elements, and a damper which closes in direction 65
from the bottommost element upwardly to serially
cut off direct access of air to the advance ends of
the spaces between the elements.

In the accompanying drawings I show that one
embodiment of my invention now best known to 70
me.

Figs. 1 and 2 are vertical, longitudinal sections
and advanced end elevation respectively of the
burner showing the positions of parts and the
coursing of the flame at the inception of starting. 75

Figs. 3 and 4 are similar views showing the
parts and current of combustibles at inception
and before complete establishment of the current.

Figs. 5 and 6 are similar views showing the
parts and the current of combustibles in the es- 80
tablished relation of continuous and high effi-
ciency operation.

The body of the burner is a casting. It com-
prises a substantially rectangular casing 10 open
85 at its ends 11 and 12. The end 11 is the inlet or ad-
vance end. The end 12 is the outlet or flame
mouth end. Advance end 11 is of substantially
plane form walls substantially at right angles to
the wall of the casing. End 12 is concavely cut
away to form the mouth of the casing extending 90
upwardly at an angle from the bottom, thereby
to better direct flames upwardly. The upper
wall of the casing contains fuel admission cham-
ber 13 near the advance end 11. The chamber is
provided with an inlet 14 for liquid fuel and an 95
exit 15 in the form of a transversely extending
opening in the form of a slot. The bottom wall
16 of the chamber is provided with an upwardly
extending bead or fuel retaining wall 17 over
which liquid fuel will trickle or drip into the 100
body of the casing 10. The bottom of the casing
is provided at its opposite ends respectively with
low retaining walls 18 and 19, to constitute in the
bottom of the casing a receptacle to receive and
hold liquid fuel.

Intermediate the bottom and top walls of the
casing 10 are cast extending from one side wall
to the other of the casing, a plurality of vapor-
izing plates 20, 21 and 22. These plates are sub-
stantially horizontally arranged in vertically 110

spaced relation such that they define between themselves and the upper and lower walls of the casing 10 vaporizing channels 23, 24, 25 and 26. The plates at their ends are arranged in stepped 5 relation progressing downwardly and inwardly both at the advance end 11 and the flame mouth end 12 of the casing. The plates themselves are inclined slightly downwardly toward the flame mouth end of the casing. The inner end of the 10 uppermost plate 20 projects beyond the fuel inlet 15 from chamber 13, whereby liquid fuel dropping over bead 17 drops upon it. The outer ends of the plates are spaced inwardly of the advance end 11 of the casing, whereby there is provided 15 from the lower plates to the upper plates a channel of decreasing width between the advance ends of the plates and the advance end of the casing.

Pivoted to the plane face of the advance end 11 of the casing at 27 is damper 28 which closes 20 upwardly. This damper consists of a plate having a closing or upper edge 29 of convex outline, preferably semi-circular. When upwardly closed maximum air is admitted at the two corners 30, 31 of the casing (see Fig. 6). Damper edge 29 25 is outwardly flared to admit more air in a more orderly manner and prevent catching on edges. The area of the damper is such that when in the closed position shown in Fig. 6, the entire lower portion of the advance end 11 of the burner is 30 cut off from direct access of air.

At starting (Fig. 1) I admit liquid fuel in drops rapidly (as controlled by a needle valve of usual type with or without a sight feed as may be desired, and none of which are necessarily shown 35 here). Fuel admitted to chamber 13 overflows the bead 17 and drops in cascade (it can be easily seen from the advance end 11 of the burner) down the inner ends of the plates 20, 21, 22 to the bottom of casing 10 where it forms a pool 32. 40 Damper 28 is pulled all the way down, (see Fig. 2) opening the entire area of the advance end 11. The fuel is ignited by thrusting a piece of paper down any of the channels 23 to 26 until its end projects inwardly beyond them and lighting the 45 outer end of the paper. This may be done, preferably, before starting the flow of any oil. The flame progresses down the paper to the inner ends of the channels 23 to 26. There it ignites the incoming fuel and the flame passes to the pool 32 50 being formed in the bottom of the casing. The incoming fuel of the cascade and the pool both ignite. The flames play about all ends of the plates 20 to 22 and between them as well as upon the walls of the casing 10, heating the entire 55 structure, and particularly the walls which constitute the channels 23 to 26. This is shown especially in Figs. 1 and 2.

After several minutes of such operation, for example, about three minutes, the supply of 60 liquid fuel is considerably reduced (by half or three quarters) and the damper 28 adjusted to the position shown in Figs. 3 and 4, whereupon flames shown by the arrows as having been generally distributed at the inception of starting as 65 shown in Fig. 1, are now drawn outwardly to the advance end 11 of the burner, appearing as in Fig. 3. Mixed yellow and blue flame in the space 33 between the outer ends of channels 23 to 26 and the end 11 of the casing courses upwardly and through the channels to the inner walls of the burner. Under these conditions the pool of oil 32 soon diminishes, the flames almost, if not entirely, disappearing from the lower inner portion of the casing and the flame mouth end 70 of the lowermost channel 26, and being confined

largely to the space 33 and the channels 23 to 26 themselves.

Thereupon again the flow of oil is increased, but not to so great extent as at the inception, and simultaneously the damper 28 is moved upwardly to a position approximating that shown in Figs. 5 and 6. Immediately there is established the current of combustibles and flame shown in Fig. 5. The flame progresses upwardly of the space 33 and is by this step progressed to the mouths of the upper channels 23, 24, burning at the point 34 as a very hot blue flame, coursing inwardly through channels 23 and 24 an appreciable distance and perhaps also down through channel 25, depending on the adjustment. The current of combustibles indicated by the arrows then consists of non-burning vapor in the channel 26 admixed perhaps with some air and products of combustion from the flame mouth end 12 of the burner, but in proportions constituting it a non-burning mixture, and similar mixture in the lower portion of the space 33 between the advance ends of channels 25 and 26, and the advance end 11 of the casing; burning vapor and admixed air in the region 34 at the advance ends 100 of channels 23 and 24, the air being admitted and regulated by the damper 28; excess air admitted by the damper 28 and burning vapor progressing forwardly through the main bodies of the channels 23 and 24; burning vapor produced by the 105 contact of the liquid fuel with the hot walls of the channels as it cascades down the inner ends of those walls, burning with the excess heated air of the combustibles moving forwardly through the channels 23 and 24 and perhaps 25; a great 110 hot blue flame flaring from the mouths of the channels 23 and 24, and finally excess liquid fuel cascading to the bottom in that small amount necessary to maintain vaporization in channel 26 and perhaps also in channel 25. The vapor of 115 this admixed with the air and products of combustion from the flame mouth 12 repeat the cycle as they ascend the space 33.

I do not know all the reasons for the high efficiency which my invention makes possible in this 120 type of burner. I am not sure that all of the reactions recited take place in precisely the relation stated, but I am sure that the combustibles course as set forth and are constituted as set forth and that current is established by the use 125 of the apparatus, and it is used in the manner I have described. I believe that these effects are due to the draft action of the existing flame from the mouth 12, and the draft action of the flames which are progressed upwardly from the bottom 130 of the casing 10 through the space 33 to its upper portion 34. The main flame from the flame mouth 12 and the flame mouth ends of the channel 23 to 26 constitutes a draft so strong that flow in the course outlined by the arrows and 135 which has been mapped by me from actual observation, as shown in Fig. 5, becomes the only possible course when the damper is adjusted to its closed position, as shown in Fig. 6. Insufficient air due to the relative closure of the furnace in 140 which the burner is placed and the general prevalence of products of combustion in the flame mouth 12 preclude burning in channel 26 and perhaps in channel 25 when the damper is closed, and enable me to progressively shift the flame 145 backwardly through the channel 26 and also of the space 25 with the progress upwardly of the damper. There is probably a draft effect incident to the upward rise of the space 33 and the upward inclination as respects the advanced end 11 150.

of the casing of the plates 20, 21 and 22 which constitute the channel walls. There is probably also an entraining action of the air which enters through the space 34 under the influence of the natural draft of the device. But the fact is, as I have stated, that the current of combustibles and in due course the flames are progressed backwardly through channel 26 and perhaps channel 25 upwardly through the space 33, and thence forwardly through channels 23 and 24 to the flame mouth end in high draft. I believe the initial heating by the pool of Fig. 1 to heat mainly the end walls of the channels 23 to 26 and exposed walls of the casing 10; the advanced flame of Fig. 3 to heat both their end walls of the channels 23 to 26, and the inner walls, particularly the inner walls of the upper channels, and to a considerably higher temperature than at the start; and the pure blue flame which burns in the region 34 to heat the walls of the upper channels 23, 24 to yet higher degrees, and at the same time, super-heat all excess air which may be admixed in this region, whereby the greater part of the incoming liquid fuel is promptly and fully vaporized and admixed and burnt. It would seem too, that the admission of the greater quantities of air in opposite corners 30 and 31 provides not only a more general distribution of the blue flame burning in the region 34, but also the more thorough admixture with the uprising vapor from space 33, particularly since the major volume of that vapor rises through the central portion of the space 33, and finally gives a more thorough admixture and more uniform distribution of the mixture in the expanse of the channels 23 and 24.

The results of high efficiency I have above set forth.

In the annexed claims each and all modifications of my invention which do not depart from this generic spirit are to be comprehended.

What I claim is:

1. A vaporizing oil burner comprising a casing containing vaporizing elements defining a vertically arranged series of vaporizing channels, means to supply liquid fuel to the upper channels, and a damper for one end of the channels which closes from the lowermost channel upwardly to serially cut-off channels from direct access of air.

2. A vaporizing oil burner comprising a casing having air inlet and flame outlet openings therein and containing a stack of substantially horizontally arranged vertically spaced plates, means to admit liquid fuel to the upper of said plates, and a damper which closes from the bottommost of said plates upwardly.

3. A vaporizing oil burner comprising a substantially rectangular casing having air inlet and flame outlet openings therein and containing a stack of substantially horizontally arranged spaced vaporizing plates, means to admit liquid fuel to the upper of said plates, and a damper which closes from the bottommost of said plates upwardly and is provided with a convexed upper edge, the medial line of which when the damper is in its uppermost position lies in the longitudinal plane of symmetry of the burner, whereby maximum air is admitted at the two upper corners of the burner.
